United States Patent Office

Des. 185,958

Patented Aug. 25, 1959

185,958

KNIFE

Gabriel W. Bougie, Portland, Oreg.

Application October 8, 1957, Serial No. 48,010

Term of patent 14 years

(Cl. D22—3)

I claim:

The ornamental design for a knife, substantially as shown.
